PORATION OF NEW JERSEY

NONSOILING PLASTER BACKING AND METHOD OF MAKING IT

Application filed December 17, 1929. Serial No. 414,808.

The object is to provide for plasters having non-soiling backings.

Heretofore, and before our invention, it has been the practice in the manufacture of plaster to spread adhesive mass on a cotton or other fabric of close construction. The cotton or other fabric, notwithstanding singeing and sizing or other usual finish, has innumerable fibers protruding from the threads and making for a pile, nap, or fuzzy surface. This fuzzy character of the backing is conducive to ready soiling in the necessary handling of the plaster; and it suffers the further disadvantage that when the plaster is rolled upon itself on a spool or mandrel the adhesive mass contacts the fuzzy backing and when subsequently unrolled the effect is to pull up more fibers and so make for additional soiling.

The nature of our invention consists in filming, glazing or enameling the backing in such way as to obviate the exposure or presence of loose fibers and for the purpose and with the result of providing a non-soiling backing.

In the annexed drawing

Figure 1 is a view of a form of usual backing presenting the problem, namely the fuzzy surface making for soiling.

Fig. 2 shows the same embodying the present invention.

Fig. 3 shows a view of a more or less open fabric embodying the invention.

Fig. 4 is a sectional view of a plaster embodying the invention.

Referring to Fig. 1, the element 5 is the usual close woven cotton or other fabric which has been singed and or sized or otherwise treated in the usual way of finishing such fabric, but which, nevertheless, presents when closely examined a highly developed pile, nap or fuzzy surface 6 due to the innumerable fibers protruding from the threads, which characteristic, as stated at the outset, is decidedly objectionable because it makes for ready soiling of the backing.

According to the present invention, we meet this problem by filming, glazing or enameling the usual finished surface of the backing in such way as to obviate the exposure

of fuzzy or other surfaces making for soiling. Such film, glaze or enamel may take the form of an almost imperceptible continuous water repellent film having the capacity to lay all loose or upstanding fibers and to render the material non-soiling. Such form is well adapted for close structures. For more or less open weaves or structures, it is sometimes advantageous to embed the fabric in the filming material. In any event the rough side of the fabric is beneficial to the spreading of the plaster or adhesive mass.

In the achievement of our purpose we have had marked success with the use of various types of lacquers of cellulose acetate or nitro-cellulose base, or viscose solutions. The viscosity of the solution may vary according to the thread count and the amount of film to be deposited. The solution may be applied with a brush or the fabric may be drawn through it. After the filming, the fabric may be passed over warm drums of smooth surface to eliminate the solvent and for calendering and finishing if desired. Usually we employ a transparent, opaque or colorless film, but it would be a mere continuation of our inventive thought to color it.

Fig. 2 shows our non-soiling film 7 applied to the finished side of a plaster backing 8.

Fig. 3 shows a more or less open woven backing 9 embedded in non-soiling film 10.

In Fig. 4, 11 represents the non-soiling film and 12 represents the plaster or adhesive mass.

Having described our invention, we claim:

1. In the manufacture of plaster of the character set forth, the method which consists in singeing one surface of the foundation fabric and then applying to that surface a film of cellulose acetate for the purpose and with the result of laying the fuzz or fiber-down and to present a water-repellent, non-soiling, non-sticking, smooth-finished surface, and applying adhesive mass to the other or rough side of the fabric, said film being essentially superficial as to depth so as not to impair the flexible or pliable properties of the fabric.

2. A plaster consisting of close woven fab-

ric whereof one side is singed and filmed with cellulose acetate to cover any attendant fuzz, and whereof the other side is relatively rough and covered with adhesive mass.

5 In testimony whereof we affix our signatures.

GUSTAVE S. MATHEY.
CHARLES F. SLOTTER.
